UNITED STATES PATENT OFFICE.

JAMES L. GRIBBLE AND GUY L. WILLETT, OF LOUISVILLE, KENTUCKY.

ADVERTISING DEVICE.

1,266,014.

Specification of Letters Patent. Patented May 14, 1918.

Application filed January 15, 1917. Serial No. 142,409.

To all whom it may concern:

Be it known that we, JAMES L. GRIBBLE and GUY L. WILLETT, citizens of the United States, and residing in the city of Louisville, 5 county of Jefferson, and State of Kentucky, have invented a new and useful Improvement in Advertising Devices, of which the following is a specification.

This invention relates to advertising devices, more particularly such as are applicable to sign boards located along public thoroughfares.

Advertisements and sign boards are used for the purpose of conveying information, 15 many expedients being used to attract attention to the subject matter thereof. Pictorial representations are extensively used for the purpose, as they attract attention readily, linger in the memory and when 20 recalled, are apt to be associated with the subject matter which they accompanied. It is recognized that the mysterious or that which excites the curiosity of the observer makes the most lasting impression on the mind.

An object of this invention is to provide 25 means for attracting attention to a sign which by the mystery thereof, excites curiosity as to its mode of operation and creates a lasting impression on the memory of an 30 observer.

A further object is to provide means for displaying, in connection with a sign, pictorial representations which will fade, vanish, and change characteristics before the 35 eyes of an observer in a mysterious manner.

With the foregoing and other objects in view, the invention consists of the novel construction and arrangement of parts illustrated in the accompanying drawings, which 40 form a part of this specification, wherein is set forth an embodiment of the invention, but it is to be understood that such changes and modifications may be resorted to as come within the scope of the appended 45 claims.

In the drawings, wherein similar reference characters designate like parts in the several views, Figure 1, is a front elevation of a sign-board embodying our invention; 50 Fig. 2, a section on line 2—2 of Fig. 1; Fig. 3, a section on line 3—3 of Fig. 2; Fig. 4, a perspective view of the exhibition box.

Referring now to the drawings, the reference character —10— designates a sign- 55 board which may be of any desired or suit-

able construction. This board is provided with a sight opening —11— which may be bordered with a molding —12— and closed by a pane of glass to give it the appearance of a picture frame. In the rear of the sign-board and spaced a suitable distance therefrom is a dark chamber —13— provided with an opening —14— which registers with the opening 11 in the sign-board. The intervening space —15— between the sign board and the chamber is bridged by inclined boards —16— making a light tight connection. Within the chamber an exhibition box —17— is suspended in such a manner that its angle of inclination to the sign-board may be varied. As illustrated the mode of suspension comprises hooks —18— secured to the front wall of the chamber and pins —19— extended laterally from the upper forward corners of the box. Any suitable means of retaining the box in adjusted position may be employed, the means illustrated comprising a hook —20— depending from the top of the chamber and adapted to be engaged in a selected perforation in 75 a plate —21— secured on the box. The box is substantially quadrangular in shape and light tight; it has a frontal opening —22— which extends from the top of the box to within a spaced distance of the bottom, and 80 is so hung that the opening 22 coincides with the openings 11 and 14. Reflectors —23, 24— which may be of any suitable pattern are disposed across the box in the lower rear corner thereof, and are respectively adapted to direct rays of light from 85 a suitable source of light, such as a series of electric lamps —25, 26— against the back —27 and bottom —28 of the box. The rays from a series of lamps —34— are directed against the bottom by a reflector —60— and against the back from a series of lamps —35— by a reflector —61—. The lamps, which are arranged along the respective reflectors, are in separate circuits and 90 the wires —29, 30— and —31, 32— thereof are led to a suitable device —33— known as a dimmer, which is adapted to control the lamps in the respective circuits turning them off or on, and increasing or diminishing their luminosity as occasion requires. 95 Dimmers constitute mechanism well known in the art pertaining to illumination, and need not be described in detail. Suffice it to say that they comprise a series of disks 100

105

110

positioned upon a shaft, one for each circuit, each disk having peripheral conducting and non-conducting sections upon which contact springs bear, the sections being prearranged 5 in such relationship as to produce the desired lighting effect. The conducting sections may be arranged to introduce a resistance into the circuit to dim the light before extinguishing the same. A pictorial representation —36— (Fig. 1) is placed on the rear wall of the box. As illustrated this representation is that of a hand holding a number of rent receipts, and a legend "All you have to show if you pay rent". This 10 picture being on the rear wall of the darkened box, is not visible to an observer standing in front of the sign-board except when illuminated by the lamps 25, and as the lights grow dim and go out, the bunch of 15 rent receipts gradually fade away. On the bottom of the box, is a pictorial representation, or other suitable object, which may be either complementary or supplementary of the presentation on the back. As illustrated 20 the picture on the bottom is that of a house, or home —37— with the caption "The home you may buy". This picture being on the bottom of the box, cannot be viewed, by direct vision from the front of the sign, 25 but when illuminated, by the lamps 26 and 34, the rays of light projected upward from the picture will be intercepted by a pane of clear glass —38— disposed at an angle of 30 45 degrees, and be reflected forward thereby 35 in the same plane as the light rays from the picture on the back of the box. If one picture be illuminated while the other is not, the one illuminated will appear to an observer as if on the back of the box. If the 40 light be gradually dimmed and at the same time the other picture be gradually illuminated, the one will appear to fade away while the other mysteriously appears in its place. If both pictures are illuminated at 45 the same time, they will appear to an observer as if superimposed on the back of the box. In the example illustrated the upper picture is illuminated for say three seconds, thus displaying the handful of rent 50 receipts. Then during a period of say six seconds, the light is gradually diminished and then extinguished leaving the picture dark and invisible, the rent receipts seeming to dissolve and fade away. At the same 55 time the light is gradually turned on the lower picture and the house appears to grow, gather substance and finally supplant the rent receipts. The house is displayed for a period of say fifteen seconds and the light 60 then turned off leaving the box dark. After a period of say thirty seconds the lights are again turned on the upper picture and the foregoing cycle repeated. It is to be observed that the use of rent receipts and a 65 house is merely illustrative as any desired

or suitable subject may be utilized. If a pictorial representation of an object at rest, say a horse standing on its four feet, be placed on the back, and a picture of the same object in a different position say reared 70 up on its hind feet, be placed on the bottom of the box, and the pictures illuminated alternately, at intervals of say one half second, without any interval of darkness, the object will present the appearance of continuous motion. The device as described may be best displayed at night when an observer can see the interior of the box only by interior illumination. Diffusion of daylight through the sight openings renders the 80 pictorial representations pale and inefficient; consequently a shade or curtain —39— is provided which is adapted to be drawn down so as to close the sight opening during the day, the shade bearing a replica of the 85 main figure of the interior presentation. The exhibition box may be constructed of any suitable material and in any manner suited to its use. As illustrated it comprises end frames —40—, said end frames consisting of main vertical members —41, 41—, main horizontal members —43, 44—, secondary vertical and horizontal members —45, 46— and diagonal brace members —47—. The top —48—, bottom —49—, back —50— 90 and the lower portion —51— of the front of the box are transversely sheathed with tongue and grooved boards. Each end of the box is closed by two groups of boards —52, 53— which extend respectively from 95 the lower and rear edges of the frame 40, on the inner side thereof to within a spaced distance of the center of the diagonal braces 47, thereby forming grooves, or slots —54— adapted to receive the pane of glass 38, the 100 lower edge of which rests upon a transverse beam —55— (see Fig. 2). The reflectors 23, 24 and associated lamps 25, 26 are arranged as a unitary structure and are adapted to be removably attached to the box in 105 the corner thereof between the members 42 and 44 by suitable means such as screws —56—. When the unitary reflector structure is removed, a board or tray —58— which lies on the bottom of the box, may 110 be withdrawn for the purpose of changing the picture or other object thereon. The back 50 is detachably secured to the frame 40 by suitable means such as screws whereby it may be removed to change the picture 115 carried thereby.

Having thus described our invention so that anyone skilled in the art pertaining thereto may make and use the same,

We claim:

1. In apparatus as characterized, a dark chamber having an opening in a wall thereof, a box within said chamber, hooks positioned on the wall of the chamber above the said opening, means extended from the for- 130

ward portion of said box and adapted to be engaged in said hooks, and means extended from a wall of the chamber and adapted to be adjustably engaged with the rear of the 5 box to hold it at different angles to the opening.

2. In apparatus as characterized, a dark chamber, an exhibition box, said chamber and box having aligned sight openings, a 10 transparent reflecting medium suitably positioned within the box, a reflector removably positioned in a corner of the box, and means for adjusting the box at an angle to the sight opening in the chamber.

15 3. In apparatus as characterized, a chamber having a frontal sight opening, a light tight exhibition box suspended within said chamber, said box having an opening in

alignment with the frontal opening in the chamber, a transverse beam within the box 20 in proximity to a rear corner thereof, a pane of glass extended from said beam to the corner of the box opposite thereto, a removable back on the box, a removable tray within the box, said back and tray adapted 25 to carry objects to be exhibited, illuminating means removably positioned in the rear of the transverse beam, said illuminating means comprising a double faced reflector adapted to reflect light respectively on the 30 back and tray and means for alternately illuminating the back and tray.

JAMES L. GRIBBLE.

GUY L. WILLETT.
